CHARLES H. TOWER, OF CLEVELAND, OHIO, ASSIGNOR TO THE TEAGLE COMPANY, OF CLEVELAND, OHIO, A CORPORATION OF OHIO.

SYSTEM AND APPARATUS FOR GENERATING AND DISTRIBUTING ELECTRIC CURRENTS.

Original application filed December 12, 1918, Serial No. 266,437. Divided and this application filed April 26, 1923. Serial No. 634,659.

This invention relates to a system for generating and distributing electric currents and has to do more especially with an apparatus adapted to generate low tension current for battery charging purposes and high tension current for ignition purposes for use in connection with internal combustion engines and especially engines used for automotive purposes.

10 The principal object of the invention is the provision of apparatus comprising a low tension direct current generator, a high tension ignition current generator and a storage battery and having means for insuring 15 strong ignition currents at low engine speeds.

20 A further object of the invention is the provision of apparatus such as last referred to having means for insuring strong ignition currents at low engine speeds even when the storage battery is out of commission.

25 Another object of the invention is the provision of apparatus of the character in question having a low tension generator with satisfactory characteristics under normal operating conditions and with a sufficiently low pick-up speed to excite the high 30 tension generator strongly enough to give a satisfactory spark by hand cranking in case the battery gets out of order.

35 Further objects of the invention, more or less incidental to the foregoing, will appear in the following description in connection with the accompanying drawings, in which I show several preferred embodiments of the invention.

40 In the drawings, Fig. 1 is a diagram of one form of my improved apparatus. Fig. 2 is a diagram of an alternative form of construction.

Fig. 3 is a diagram showing another alternative form of construction.

45 The present application is a division of my earlier application, Serial No. 266,437, filed December 12, 1918, upon which has been granted Letters Patent No. 1,466,635, and reference may be had to said earlier application for a detailed showing and description of parts which in the present application are not shown or are shown only diagrammatically.

Referring first to the form of apparatus shown in Fig. 1, the combined low tension generator and high tension generator unit 55 has a rotor shaft 8 on which is mounted the direct current armature 11 of the low tension generator, said armature having a commutator 11^a. This armature is of standard construction. The shaft 8 also carries the 60 rotor of the high tension generator, the laminated iron core (not shown) of said rotor having mounted thereon an exciting winding consisting of two coils 12^b which are formed with a sufficient number of turns 65 of sufficiently fine wire to insure at the same time both ample excitation and a very moderate draft of current.

The usual brushes 13, 14 cooperate with the commutator 11^a, the brush 14 being 70 grounded as indicated. The low tension generator is excited by a winding comprising coils 15, 16 which are mounted on diametrically opposite field poles in the usual manner, one terminal of the winding being 75 connected to the brush 13 while the other terminal of the winding is connected to a third brush 17 which is designed to afford the so-called third brush regulation for the low tension generator. 80

The exciting coils 12^b may be suitably connected in series or parallel, according to the size and length of the winding. As shown they are connected in series, one end of the winding being grounded and the other end 85 being connected to a collector ring 18 which is mounted on a disc 19 of insulating material carried by the shaft 8. A brush 21, carried by the stator of the generator unit, contacts with the collector ring 18 and is 90 connected through a lead 22 with the commutator brush 13 of the low tension generator.

On a suitable polar extension (not shown) of the stator structure and in inductive relation to the rotor winding 12^b, is mounted a high tension generating winding 29 comprising a coarse section 29^a and a fine section 29^b. One end of the coarse section 29^a is grounded while its other end is connected 100 at 30 to one end of the fine winding 29^b. The other end of said fine winding is connected by a lead 37 to the inner end of a rotary distributor arm 53. The outer end

of the distributor arm is arranged to move successively through points adjacent to the several terminals 55, 55 of high tension leads 55^a, 55^a that extend to spark plugs 56 of the cylinders of the engine in connection with which the apparatus is used. The arm 53 is mounted on a shaft driven from the shaft 8 of the generator.

The breaker mechanism of the high tension generator comprises a fixed electrode 59 which is adjustably mounted on a suitably supported holder 60. A movable electrode 62 is carried by a pivoted arm 63 which is arranged to be actuated by cam 65 mounted on the shaft which carries the distributor arm 53. 69 is a condenser connected across the breaker electrodes in the usual manner. The fixed electrode 59 of the breaker is connected by a lead 70 with the junction point 30 of the coarse and fine sections 29^a and 29^b of the high tension winding.

71 is a storage battery, one terminal of which is grounded while its other terminal is connected through lead 22, with the low tension generator brush 13 and with the collector ring 18 through which current is supplied to the exciting winding 12^b of the high tension generator. A cut-out mechanism 72, which is designed to automatically open the circuit when the voltage of the low tension generator falls below a certain value and to close the circuit when the voltage rises above this value, is interposed between said generator and the battery 71.

The movable electrode 62 of the breaker is connected by a lead 73 with a switch 74 by means of which the said electrode is normally connected to ground but can be connected through lead 75 with the storage battery 71 and, when the cut-out 72 is closed, with the terminal of the low tension generator.

A switch 76 is provided to break the circuit through the lead 22 for the purpose of stopping the engine.

The operation of the apparatus is as follows: On starting the engine, the spark first having been retarded in the usual manner by adjustment of the breaker housing (not shown) and the cut-out 72 being open by reason of the low speed of rotation, current flows from the storage battery 71 through the lead 22, brush 21 and collector ring 18 to the exciting winding 12^b of the high tension rotor. As said rotor turns its magnetic flux is passed through the adjacent stationary high tension winding 29 first in one direction and then in the other so that the flux through said high tension winding is first increased and then decreased. While the flux is decreasing the breaker closes and current flows in the short circuited coarse section 29^a of the generating winding. With the continued

movement of the rotor the flux through the generating winding continues to decrease and at a suitable point the cam 65 causes the breaker to open, whereupon, the current in this section of the coil being interrupted, a rapid collapse of the flux follows and the consequent rise in potential in the fine section of the generating winding causes the current to break down the dielectric in the gap of the spark plug of the engine cylinder with the production of the ignition spark. The continued rotation and consequent further flux decrease generates an electro-motive force which sustains the spark current for an appreciable length of time, just as in the case of the direct high tension magneto. As the rotation continues the above cycle of operation is repeated and the ignition current is successively distributed to the engine cylinders in the well-known manner.

When the speed of the generator has increased until its voltage is equal to or greater than the voltage of the battery, the cut-out 72 operates to close the circuit, whereupon current flows from the low tension generator to charge the battery and to energize the exciting winding 12^b of the high tension generator. As the engine comes up to speed the spark can be advanced in accordance with the usual practice.

In starting the engine, should there be any difficulty in securing satisfactory ignition, as when the engine is turned over very slowly, the switch 74 can be shifted to connect the battery 71 through lead 75 with the movable electrode of the breaker, whereupon the electro-motive force of the battery is combined with that due to the movement of the high tension rotor to generate current in the coil 29^a when the breaker is closed. Of course the electro-motive force generated by the turning of the rotor is alternately added to and subtracted from that of the battery, but as the generated electro-motive force due to the slow turning of the rotor is very much smaller than that of the battery, a satisfactory ignition spark is secured even when the respective electro-motive forces are in opposition.

In Fig. 2, showing a modified form of my apparatus, where reference characters similar to those in Fig. 1 are employed they represent similar parts or devices which need not again be described. The object of this modified construction is to insure satisfactory ignition even when the battery is for any reason inoperative and hand-cranking is necessary. The low tension generator is provided with exciting coils 77 and 78 which supplement the coils 15 and 16. The coil 77 is connected with the brush 13 of the generator with which coil 15 is connected, and the coils 77 and 78 are connected together in series, one terminal of the last named coil being connected through a lead

79 with one of the terminals of a switch 74^a which replaces the switch 74 of the apparatus shown in Fig. 1. The switch 76 shown in Fig. 1 is here replaced by switch 76^a which is interposed in the lead 22 and has an additional terminal which is connected by lead 80 with the lead 79.

With this modified system the battery current obviously can be employed for starting just as in the case of the system shown in Fig. 1, said current being passed either through exciting winding 12^b alone or through both winding 12^b and coarse section 29^a of the high tension generating winding. But if the battery should for any reason be out of order or inoperative and hand-cranking necessary to start the engine, satisfactory ignition can be secured by means of current from the low tension generator. For this purpose switch 74^a is thrown to connect leads 73 and 79 and the switch 76^a is thrown to connect the lead 80 and the lead 22. Thereupon current from the brush 13 of the generator not only flows through exciting coils 15 and 16 but also through the exciting coils 77 and 78 and thence through switch 74^a to the coarse section 29^a of the high tension generating coil and through switch 76^a to the exciting winding 12^b of the high tension generator. With this system of windings and connections exciting coils 77 and 78 are connected in series with the load and the low tension generator picks up quickly and furnishes a sufficiently strong current to the coils of the high tension generator to insure adequate ignition current.

In Fig. 3 I have shown another modified form of connections and windings for the generator which is designed to accomplish in another way the results secured by the system shown in Fig. 2. As in the case of Fig. 2, parts and devices similar to those in Fig. 1 are designated by similar reference characters. In the present system lead 22 of Fig. 1 is replaced by a lead 22' which extends from the brush 13 of the low tension generator to one terminal of a switch 81, and a lead 22^a which extends from a terminal of the said switch to the brush 21. The lead 22' is also connected to one terminal of a switch 82 with which lead 73 is connected. 83 is a lead extending from lead 22' (preferably connected therewith between brush 13 and cut-out 72) to one of the terminals of a three-pole double throw switch 84.

In the present case the exciting winding of the low tension generator consists of two coils 85 and 86 which are connected together in series, the terminal of coil 85 being connected with brush 17 while the terminal of coil 86 is connected by lead 87 with one of the terminals of switch 84. A lead 88 connects one of the terminals of

switch 84 with a terminal of switch 81, and a lead 89 connects a terminal of switch 84 with one of the terminals of switch 82.

In the operation of the last described system, if the battery is in working order current from it can be used for ignition purposes when starting by moving the switch 84 to its lower position and connecting lead 22' with leads 22^a and 73 through switches 81 and 82 respectively; or if desired the battery can be connected only to the exciting winding 12^b, the movable electrode of the breaker being connected to ground by switch 82. But if the battery is out of order and cranking by hand is necessary, adequate current for ignition purposes can be drawn from the low tension generator by throwing switch 84 to its upper position and moving switches 81 and 82 to their full line positions. Current then flows through the exciting windings 85 and 86 and then by way of switch 84 and the breaker to the coarse section 29^a of the high tension generating coil, and also by way of the switch 84, switch 81 and lead 22^a to the exciting coil 12^b of the high tension generator. As the coils 85 and 86 in this case have a series connection the low tension generator picks up rapidly and generates a sufficiently strong current to insure satisfactory ignition at starting speeds.

When the engine is started the switch 84 can be thrown to its lower position whereupon the exciting coils 85 and 86 and also the movable electrode of the breaker are connected to ground while the low tension generator is connected through lead 83, switch 81 and lead 22^a with the exciting winding 12^b of the high tension generator.

When current for ignition purposes is drawn through the series exciting coils 85 and 86, the fact that the circuit through the coils or primary windings 29^a is periodically interrupted does not interfere with the picking up of the low tension generator since there is a steady draft of current from the exciting coils 85 and 86 by way of the exciting coil 12^b of the high tension generator. In this respect the actions of the two systems shown in Figs. 2 and 3 are similar, there being in each case a continuous draft of current through the exciting winding 12^b.

While in each of the three forms of construction set forth there is cooperative interaction between the low tension and high tension generators, it will be observed that not only does neither generator interfere in any way with the functions of the other but their interaction, as has been explained, results in the shortening of the time of picking up of the low tension generator.

It is to be understood that the forms of construction illustrated can be modified in various respects without departing from my

invention, the scope of which is indicated by the appended claims.

What I claim is:—

1. In a system of generating and distributing low tension direct current and high tension ignition current, the combination with a high tension generator comprising a generating winding having a coarse section and a fine section, an exciting winding for establishing a magnetic field in inductive relation to the generating winding, means for varying the flux of said field through said generating winding, and a circuit breaker for opening and closing the circuit through the coarse section of the high tension generating winding, of a low tension generator, a storage battery, and connections between the high tension generator, low tension generator and storage battery whereby current can be drawn from the low tension generator to energize the exciting winding of the high tension generator and to charge the storage battery or current can be drawn from the storage battery to energize the exciting winding and the coarse section of the generating winding of the high tension generator.

2. In a system of generating and distributing low tension direct current and high tension ignition current, the combination with a high tension generator comprising a generating winding having a coarse section and a fine section, an exciting winding for establishing a magnetic field in inductive relation to the generating winding, means for varying the flux of said field through said generating winding, and a circuit breaker for opening and closing the circuit through the coarse section of the high tension generating winding, of a low tension generator having an exciting winding normally connected in shunt relation to the load but adapted to be connected in series with a load, a storage battery, and connections between the high tension generator, low tension generator and storage battery whereby current can be drawn from the low tension generator independently of its exciting winding to energize the exciting winding of the high tension generator and to charge the storage battery or current can be drawn from the low tension generator through its said exciting winding to energize the exciting winding and the coarse section of the generating winding of the high tension generator.

tension generator and storage battery whereby current can be drawn from the low tension generator independently of said series exciting winding to energize the exciting winding of the high tension generator and to charge the storage battery or current can be drawn through said series exciting winding of the low tension generator to energize the exciting winding and the coarse section of the generating winding of the high tension generator.

3. In a system of generating and distributing low tension direct current and high tension ignition current, the combination with a high tension generator comprising a generating winding having a coarse section and a fine section, an exciting winding for establishing a magnetic field in inductive relation to the generating winding, means for varying the flux of said field through said generating winding and a circuit breaker for opening and closing the circuit through the coarse section of the high tension generating winding, of a low tension generator having an exciting winding normally connected in shunt relation to the load but adapted to be connected in series with a load, a storage battery, and connections between the high tension generator, low tension generator and storage battery whereby current can be drawn from the low tension generator independently of its exciting winding to energize the exciting winding of the high tension generator and to charge the storage battery or current can be drawn from the low tension generator through its said exciting winding to energize the exciting winding and the coarse section of the generating winding of the high tension generator.

In witness whereof, I hereunto affix my signature.

CHARLES H. TOWER.
